UNITED STATES PATENT OFFICE

168,670

STOCK DRYING OVEN FOR COATED SHEETS OR THE LIKE

James A. Black, Grand Rapids, Mich.

Application November 9, 1951, Serial No. 17,338

Term of patent 14 years

(Cl. D81—1)

To all whom it may concern:

Be it known that I, James A. Black, a citizen of the United States, residing at Grand Rapids, in the county of Kent and State of Michigan, have invented a new, original, and ornamental Design for a Stock Drying Oven for Coated Sheets or the like, of which the following is a specification, reference being had to the accompanying drawings, forming a part thereof. In the drawings:

Figure 1 is a front and side perspective view of a stock drying oven for coated sheets or the like, showing my new design; and

Figure 2 is a rear and side perspective view of the same.

The opposite side of the stock drying oven for coated sheets or the like, which side is not shown on the drawing, is substantially like the side

shown, except that the motor and bracket support are not present on the opposite side of the oven. The top of the oven between the two upper extensions is closed and is substantially plain.

I claim:

The ornamental design for a stock drying oven for coated sheets or the like, substantially as shown and described.

JAMES A. BLACK.
